(57) **CLAIM**

The ornamental design for a tool bag, as shown and described.

DESCRIPTION

FIG. 1 is a perspective view of a tool bag according to an embodiment of the invention.

FIG. 2 is a first side view of the tool bag shown in FIG. 1.

FIG. 3 is a second side view of the tool bag shown in FIG. 1.

FIG. 4 is a third side view of the tool bag shown in FIG. 1.

FIG. 5 is a fourth side view of the tool bag shown in FIG. 1.

FIG. 6 is a top view of the tool bag shown in FIG. 1.

FIG. 7 is a bottom view of the tool bag shown in FIG. 1.

FIG. 8 is a perspective view of a tool bag according to an embodiment of the invention.

FIG. 9 is a first side view of the tool bag shown in FIG. 8.

FIG. 10 is a second side view of the tool bag shown in FIG. 8.

FIG. 11 is a third side view of the tool bag shown in FIG. 8.

FIG. 12 is a fourth side view of the tool bag shown in FIG. 8.

FIG. 13 is a top view of the tool bag shown in FIG. 8; and,

FIG. 14 is a bottom view of the tool bag shown in FIG. 8.

The ornamental design which is claimed is shown in solid lines in the drawings. The broken lines in the drawings illustrate portions of the tool bag that form no part of the claimed design.

1 Claim, 14 Drawing Sheets
